[57] CLAIM

The ornamental design for a hockey puck case, as shown and described.

DESCRIPTION

FIG. 1 is a perspective view of a hockey puck case showing my new design, with the lid in a closed position;

FIG. 2 is a top plan view thereof;

FIG. 3 is a front elevational view thereof;

FIG. 4 is a left-side elevational view thereof; the right-side

elevational view being a mirror image thereof;

FIG. 5 is a rear elevational view thereof;

FIG. 6 is a bottom plan view thereof; and,

FIG. 7 is a perspective view with the lid shown in an open position.
